UNITED STATES PATENT OFFICE.

HENRY LOMO, OF CHICAGO, ILLINOIS.

HOUSEHOLD APPLIANCE.

Application filed July 13, 1925. Serial No. 43,255.

My invention relates to household appliances and particularly to collapsible household appliances which may be employed as tables and the like. The invention has 5 among its other objects the production of devices of the kind described, which are extremely neat and attractive in appearance, simple, convenient, compact, reliable and satisfactory for use wherever found applicable. 10 One form of the invention is embodied in a collapsible device which may be employed as an ironing board or a step ladder. The ironing board and step ladder have common supporting members and the step ladder 15 forms a base for the ironing board when the device is used as an ironing board. When the device is used as a step ladder, the ironing board may be folded out of the way. In the preferred embodiment of the invention 20 the height of the ironing board may be adjusted to suit the desires of the user. Many other objects and advantages of the construction herein shown and described will be obvious to those skilled in the art from 25 the disclosure herein given.

To this end my invention consists in the novel construction, arrangement and combination of parts herein shown and described, and more particularly pointed out in the 30 claims.

In the drawings, wherein like reference characters indicate like or corresponding parts:

Fig. 1 is a section taken through a device 35 embodying the novel features of my invention, the device being shown as it is positioned when it is used as a step ladder;

Fig. 2 is a section taken on line 2—2 of Fig. 1;

Fig. 3 is a section taken on substantially 40 the same line as Fig. 1, the device being shown in a position wherein it may be used as an ironing board;

Fig. 4 is a section taken on line 4—4 of Fig. 3;

Fig. 5 is a section taken on line 5—5 of Fig. 3; and

Fig. 6 is a section taken on line 6—6 of Fig. 5.

50 Referring for the present to Figs. 1 and 2, wherein the improved device is shown as it is arranged when it is used as a step ladder, the reference character 10 indicates legs or side supporting members of the step ladder portion proper, a plurality of steps or rungs

11 being arranged between the supporting members 10. The supporting members 10 are rigidly secured to each other by a plurality of rods 12 or the equivalent. Secured to the upper ends of the supporting members 10 are brackets 14 which carry a platform 15. Hinged to the platform 15 is a platform member 16 which may be brought into the position wherein it is shown in dotted lines in Fig. 1 to form an extension of the platform 15. Pivotedly secured to the brackets 14 by bolts 18 are legs or supporting members 19, which, together with the legs or supporting members 10, the steps 11 and the platform 15, constitute the essential parts 60 of a step ladder. The legs 10 and 19 may be locked in the positions wherein they are shown in Fig. 1 by means comprising bent bars 21 which are pivotally secured by bolts 22 to the legs 19. The free ends of the bent bars 21 carry a bolt 23 which is connected to the legs 10 by bent bars 24 and bracket members 25. The bracket members 25 are rigidly secured to the legs 10 and the bent bars 24 are pivotally secured to the bracket 65 members 25. The free ends of the bent bars 24 are apertured to accommodate the bolt 23. A pipe section 26 disposed around the bolt 23 and interposed between the free ends of the bent bars 21 provides means which 70 together with the bolt 23 and a lever 27 may be employed to clamp the bent bars 21 and 24 in a plurality of adjusted positions. As shown in Fig. 5, the lever 27 is screw-threaded 75 upon the bolt 23 and may be manipulated to clamp the free ends of the bent bars 21 and 24 against the ends of the pipe section 26, the free end of the bent bars 21 and 24 being preferably provided with rosettes 29 80 to insure that the bent bars will remain in 85 any adjusted position.

As shown in Figs. 1 and 2, the bent bars 24 are preferably provided with extensions 30 adapted to engage the bent bars 21 when the legs 10 and 19 are brought into their 90 fully extended positions. This construction insures that the device will not collapse while it is being used as a step ladder. A plurality of feet 33 are preferably secured to the legs 10 so that the device may be readily positioned as illustrated in Fig. 3 to permit it to be used as an ironing board.

55 The reference character 35 indicates a conventional ironing board, which may be of any suitable size, shape and material. Se- 105 110

cured to the under surface of the board 35 are bracket members 37 and 38. A pair of links 39 pivotally secured to the bracket 38 connect the bracket 38 with the leg members 19, the links 39 being pivotally secured to the leg members 19 by bolts 40. Pivotally secured to the bracket 37 by bolts or rivets 42 are flat bars 44, which, at their free ends, carry a bolt 45. The bolt 45 also passes 10 through the free ends of a pair of bent bars 46 which are pivotally secured to the legs 19 by bolts 48.

A lever 27^a substantially identical with the aforementioned lever 27 is screw-threaded upon the bolt 45 and may be manipulated to clamp the free ends of the bars 44 and the bent bars 46 between itself and the head of the bolt 45, a pipe section 50 being positioned upon the bolt 45 intermediate the 20 bars 44 to cooperate with the lever 27^a during the clamping operation. The bars 44 and the bent bars 46 are preferably provided with interengageable rosettes of the character illustrated in Fig. 6. The bent 25 bars 46 are preferably provided with extensions 52 which engage the bars 44 when the device is adjusted to its fully extended position, as shown in full lines in Fig. 3. The board 35 may be lowered from the position 30 wherein it is shown in full lines in Fig. 3 to any desired position such as, for instance, the one wherein it is shown in dotted lines in the same figure.

When the improved device is used as a 35 step ladder, the board 35 is preferably folded into the position wherein it is shown in Fig. 1. Obviously, when the board is in this position, it will not interfere with the placing of the step ladder in any desired 40 position. The links 39 are preferably provided to insure that the work being ironed will not come in contact with the bottom end surface of the legs 19 when the device is used as an ironing board.

Having thus described my invention, it 45 is obvious that various immaterial modifications may be made in the same without departing from the spirit of my invention; hence I do not wish to be understood as 50 limiting myself to the exact form, construction, arrangement and combination of parts herein shown and described or uses mentioned.

What I claim as new and desire to secure 55 by Letters Patent is:

1. In a device of the kind described, a pair of leg members connected by cross bars, a second pair of leg members adjustable with

respect to the first-mentioned pair of leg members, adjustable means intermediate the 60 pairs of leg members for holding the second pair of legs in an extended position, a board carried by the second pair of leg members, and adjustable means intermediate the 65 board and the second pair of leg members and cooperating with the first-mentioned adjustable means for holding the board in a plurality of adjusted positions.

2. In a device of the kind described, a pair of spaced legs, a plurality of cross bars 70 joining said spaced legs, a second pair of spaced legs connected at one end to one end of said first pair, means for adjustably spacing the other end of one pair of legs from the other end of the other pair, an ironing 75 board, said ironing board connected at one end to said second pair of legs at the end thereof opposite that connected to said first pair of legs, and means for adjustably spacing the other end of said ironing board from 80 said second pair of legs.

3. In a device of the kind described, a pair of spaced legs having cross bars connecting same, an ironing board opposite said pair of legs, a second pair of legs pivotally 85 connected adjacent one end to a point adjacent one end of said first pair of legs, said second pair of legs adjacent their other end pivotally connected to said ironing board, a pair of bars pivotally connected 90 to said first pair of legs, a second pair of bars pivotally connected to said second pair of legs, said pairs of bars pivotally connected to each other, means at the pivotal point of said pairs of bars for securing same in 95 adjusted position, a third pair of bars pivotally connected to said ironing board, a fourth pair of bars pivotally connected to said second pair of legs, and means for adjustably securing said third and fourth pairs 100 of the bars to each other.

4. In a device of the kind described, a pair of spaced legs, a second pair of legs pivotally connected thereto at one end, means for adjustably spacing the other end of said 105 second pair of legs from said first pair, a pair of links connected to said last mentioned end of said second pair of legs, an ironing board, said links connected to points adjacent one end of said ironing 110 board, and collapsible means for adjustably spacing the free end of said ironing board from said second pair of legs.

In testimony whereof, I have hereunto signed my name.

HENRY LOMO.
